(57) **CLAIM**

The ornamental design for microwavable cooking utensil, as shown and described.

DESCRIPTION

FIG. 1 is an exploded view of a microwavable cooking utensil;

FIG. 2 is an elevated view of the microwavable cooking utensil;

FIG. 3 is a side view of the microwavable cooking utensil; the opposite side view being a mirror image thereof;

FIG. 4 is a side view rotated 90 degrees from the view in FIG. 3; the opposite side view being a mirror image thereof;

FIG. 5 is a top view of the microwavable cooking utensil;

FIG. 6 is a bottom view of the microwavable cooking utensil;

FIG. 7 is a bottom view of the outer cover of the microwavable cooking utensil, shown separately for ease of illustration;

FIG. 8 is a top view without any covers of the microwavable cooking utensil;

FIG. 9 is a top view of the inner cover of the microwavable cooking utensil, shown separately for ease of illustration;

FIG. 10 is a side view of the inner cover of the microwavable cooking utensil; the opposite side view being a mirror image thereof, shown separately for ease of illustration;

FIG. 11 is a side view of the inner cover rotated 90 degrees from the view in FIG. 10; the opposite side view being a mirror image thereof, shown separately for ease of illustration;

FIG. 12 is a bottom view of the inner cover of the microwavable cooking utensil, shown separately for ease of illustration;

FIG. 13 is a top view of a basket of the microwavable cooking utensil, shown separately for ease of illustration;

FIG. 14 is a side view of the basket of the microwavable cooking utensil; the other side views being a mirror image thereof, shown separately for ease of illustration.

The broken lines showing the decorative logo in FIGS. 1, 2 and 4 are for illustrative purposes only and form no part of the claimed design.
